UNITED STATES PATENT OFFICE

GEORGE E. CAMPBELL, OF CHATTANOOGA, TENNESSEE, ASSIGNOR TO THE WHELAND COMPANY, OF CHATTANOOGA, TENNESSEE, A CORPORATION OF TENNESSEE

PORTABLE BAND-SAW MILL

Application filed April 14, 1931. Serial No. 530,086.

This invention relates to an improvement in portable band saw mills.

It has been heretofore very difficult to make a band saw mill portable for handling and for transportation from one place to another, as for instance on a truck. It is not desirable to dismantle the entire mill any more than is necessary on account of the loss of time in reassembling the mill and in lining up the parts of the mill during such reassembling. Due to the height of the band mill it has heretofore been necessary to dismantle the top part of the mill in order to make the mill portable.

In this invention, I have arranged the top housing carrying the top band wheel in such a manner that the entire top assembly swings forward on a pivot which connects it with the base of the mill, thus permitting it to swing over to one side to greatly lower the height of the mill and the center of gravity of the load, and reducing the tendency of the mill to tip over. There is a pivotal support on each side of the top housing, forming a substantial connection thereof with the base to pivotally support the top housing and the top band wheel in a substantial manner, while yet permitting the mill to be quickly made ready for moving or to be set up and aligned with little loss of time. There is no lining up necessary because the pivotal supports always maintain the proper alignment of the top band wheel and its associate parts.

The base of the mill is supported upon skids, which extend a substantial distance beyond the mill and serve as supports for the top band wheel when tilted to its lowered position, thus making the entire mill easier to transport. Furthermore, these skids serve as supports for the track-way, and by extending under the latter they furnish means for maintaining alignment between the track-way and the mill.

In the accompanying drawings:

Fig. 1 is a side elevation of the complete band mill;

Fig. 2 is a similar view with the top band wheel in reclining position;

Fig. 3 is an end elevation of the mill;

Fig. 4 is an enlarged perspective view of one of the pivots; and

Fig. 5 is a side elevation of the same.

The numeral 1 indicates skids which extend under the band mill and serve as supports for the base 2, which is supported thereupon as shown in Figs. 1 and 3; and these skids 1 extend laterally under the track-way formed by rails 3 extending at right angles to the skids and upon which the saw mill carriage 4 rides.

A shaft 5 is journaled in bearings in bottom housings 6 suspended from the base 2, and which shaft 5 carries a lower band wheel 7. The band saw is shown at 8 and extends upwardly from the lower band wheel 7 and about a top band wheel 9, supported upon a shaft 10 journaled in yokes 11 on opposite sides of the top band wheel 9.

The band saw 8 may be driven in any suitable manner, as for instance through a belt extending about a pulley 12 fixed on the shaft 5 for the lower band wheel 7, which belt may be driven from a suitable motor or engine in the usual way.

The yokes 11 are supported upon rods 13 and 14, the upper ends of which extend into the yokes 11 and support the same, while the lower end of the rod 14 is wedge-shaped as at 15 and the lower end of the rod 13 is connected with a section 16 by means of a connecting nut 17 which is manipulated by a handle 18 as shown particularly in Fig. 3. The lower end of the rod 13 is screw-threaded into one side of the nut 17 and the upper end of the section 16 is threaded into the opposite side, the threads being right and left-handed so that when the nut 17 is turned by the handle 18, the section 16 and the rod 13 will be moved in opposite directions so as to tilt the shaft 10 for the upper band wheel 9 in order to maintain proper alignment of the wheels and also to facilitate the application of the band saw thereto.

The lower end of the section 16 is wedge-shaped as shown at 19. A cross-shaft 20 has notches 21 in the upper side thereof to receive the wedge-shaped lower ends of the shaft 14 and section 16. This shaft 20 is supported on lower wedge-shaped pins 24, for

- which purpose it has lower notches 23, in which are seated the wedge-shaped pins 24 supported upon a bracket 25 carried by arms 26 which are fixed to a shaft 27 journaled in 5 bearings in top housings 28. A lever 29 is connected with an end of the shaft 27 and has its lower end bifurcated and straddling a threaded rod 30 on which an abutment 31 is threaded to engage one side of the lever 29. 10 The rod 30 is journaled in suitable bearings 32 on a side of one of the top housings 28 and is adapted to be turned by a hand-wheel 33.

Each of the top housings 28, connected together near the base, has a bracket 34 fixed to the forward bottom edge thereof, which bracket 34 is bifurcated as at 35 (see Fig. 4) to receive an ear 36 carried by a fixed bracket 37 bolted to the base 2, as by means of studs 38. The ear 36 is connected with the bifurcated portion of the bracket 34 by means of a hinge-pin 39, which extends therethrough and serves to pivotally support each top housing 28 upon the base 2.

25 Studs 40 extend upwardly from the base 2 in position to project through slots 41 formed in opposite sides of each of the brackets 34 when the top housings are in upright positions, in order to hold the same in such positions, nuts 42 being screwed onto the studs 40 for such purpose.

Brackets 43 are fixed to the back edges of the top housings 28 and receive bolts 44 which are connected with the base 2 in order to 35 hold said back edges in their proper aligned positions, and securely seated on the base 2.

Tubular columns 45 are fixed to the forward upper edges of the top housings 28 and within which the yokes 11 are slidably received. To the forward side of one of the columns 45 is fixed a guide 46 slidably receiving a saddle 47, from the forward end of which an arm 48 is pivotally suspended and carries a saw-guide 49. A supporting arm 45 50 extends upwardly from the guide 46 and supports a sheave 51, about which a cable 52 extends, one end of which cable is fixed to the saddle 47 while the other end extends over a sheave 53 and has tension weights 54 connected therewith. The sheave 53 is supported by an arm 55, which extends upwardly and outwardly from the rear side of one of the top housings 28 and is braced by a suitable brace 56.

55 The cross-shaft 20 for the tension device has a lever 57 fixed thereto, as shown in Fig. 3, which lever extends upwardly and has a lobe 58 connected therewith and from which a cable 59 extends over and is secured to a quadrant 60, which is fixed to a shaft 61 adapted to be turned by a lever 62, from the outer end of which are suspended counterweights 63, as set forth in my prior Patent No. 1,567,911, of December 29, 1925.

65 When the mill is in operation, the parts

will be in the positions shown in Fig. 1, where the band saw 8 is driven in the usual way, and tension is applied thereto by means of the cross-shaft 20 which acts through the rods 13 and 14, the cross-shaft 20 being turned by a turning of the hand-wheel 33, to swing the lever 29 laterally sufficiently to turn the shaft 27 and move the bracket 25 sufficiently to impart a slight turning to the cross-shaft 20; which in turn raises or lowers the rods 13 and 14 sufficiently to maintain tension on the band saw.

When it is desired to move the band mill from one place to another, the bolts 44 are removed and the nuts 42 are removed from the studs 40, and after the removal of the saw 8 and proper disposition of the counter-weights 54 and 63, the top housings 28 may be swung from the position shown in Fig. 1 to the position shown in Fig. 2, where the top band wheel 9 rests upon a block 64 carried by the skids 1 and a similar block 65 is used to support the saw guide 49. The parts are then in a position for transporting to a different place, as for instance on a truck or the like, and by reason of the lowering of the structure there is less likelihood of the mill tipping over as the center of gravity is substantially lowered, which facilitates the transportation of the entire mill without completely disassembling the parts.

After being moved to a new location, where it is desired to set up the mill again, it is only necessary to swing the top housings 28 to their upright positions and secure them by the bolts 44 and the nuts 42 on the studs 40 and to apply the band saw and the counter-weights, after which the parts are ready for operation.

No aligning of the parts is required because the alignment is maintained by reason of the pivotal supports for the top housings 28.

I claim:

1. In a band mill, the combination of a base, one or more top housings for supporting an upper band wheel for the mill, means for pivotally connecting one side of each of the top housings to the base to permit swinging of the upper band wheel to a lowered position, and detachable fastenings connected between the base and the opposite side of each of the top housings for detachably fastening the top housings in upright positions to hold the same against swinging movement on the pivotal means.

2. In a band mill, the combination of a base, a lower band wheel associated with the base in a position normally fixed relative thereto, one or more top housing supported by the base and extending upwardly therefrom, a top band wheel carried by the housings, a band saw extending about the band wheels, driving means therefor, and means pivotally connecting the top housings with

the base and permitting swinging movement thereof and relative to the lower band wheel to lower the top band wheel to a reclining position relative to the base.

5. In a band mill, the combination of a base, a lower band wheel associated therewith, driving means for said band wheel, one or more upright top housings supported upon the base and extending upwardly therefrom, an upper band wheel carried by the top housings, a band saw extending about the band wheels, a bracket carried by each of the top housings, a bracket secured to the base and associated with the first-mentioned bracket, and a pivot pin extending through the brackets to connect the same together and permit swinging movement of the top housings relative to the base.

4. In a band mill, the combination of a base, a lower band wheel associated therewith, driving means for said band wheel, one or more top housings supported upon the base and extending upwardly therefrom, an upper band wheel carried by the top housings, a band saw extending about the band wheels, a bracket carried by each of the top housings, a bracket secured to the base and associated with the first-mentioned bracket, a pivot pin extending through the brackets to connect the same together and permit swinging movement of the top housings relative to the base, and bolts arranged between the base and the brackets carried by the top housings for detachably securing the top housings rigidly in upright positions on the base and against swinging movement.

5. In a band saw mill, the combination of beams, a base structure fixed to the beams and carrying a band-wheel, a top housing arranged above the base and carrying a top band-wheel, the beams being extended beyond the base and means for pivotally supporting the top housing on the base and constructed and arranged to permit swinging of the top housing relative to the lower band wheel to an approximately horizontal position with the top band-wheel resting on the beams beside the base.

6. In a band saw mill, the combination of beams, a base structure fixed to the beams and carrying a band-wheel, a top housing arranged above the base and carrying a top band-wheel, the beams being extended beyond the base means for pivotally supporting the top housing on the base and constructed and arranged to permit swinging of the top housing to an approximately horizontal position with the top band-wheel resting on the beams beside the base, and detachable means for normally securing the top housing in a rigid upright position and against swinging movement.

7. In a band saw mill, the combination of a base, a lower band-wheel associated therewith, driving means for said band-wheel, one

or more top housings supported by the base, and extending upwardly therefrom, an upper band-wheel carried by the top housings, a band-saw for the band-wheels, a bracket carried by each of the top housings, a bracket secured to the base and associated with the first-mentioned bracket, a pivot pin extending through the brackets to connect the same together for swinging movement of the top housings relative to the base, and bolts arranged between the base and top housing brackets for detachably securing the top housings rigidly in upright positions on the base and against swinging movement.

8. In a band saw mill, the combination of a base, one or more top housings extending upwardly from the base, a bracket carried by each top housing, a bracket secured to the base and associated with the first-mentioned bracket, a pivot pin extending through the brackets to connect the same together for swinging movement of the top housings relative to the base, and bolts arranged between the base and top housing brackets for detachably securing the top housings rigidly in upright positions on the base and against swinging movement.

9. In a band saw-mill, the combination of a base, a top housing extending upwardly from the base, a bracket having an upright face fixed to the forward bottom edge of the top housing, said bracket being bifurcated, a second bracket fixed to the top side of the base and having an upstanding ear received within the bifurcated portion of the first-mentioned bracket, and a hinge-pin extending through the bifurcated portion and the ear for pivotally connecting the brackets together.

10. In a band saw-mill, the combination of a base, a top housing extending upwardly from the base, means pivotally connecting the forward lower edge of the housing with the base, and detachable fastening means connecting the opposite lower edge of the housing with the base.

11. In a band saw mill, the combination of a plurality of beams arranged in approximately parallel relation, a saw mill base supported upon the beams, a band wheel carried by the base, a second band wheel supported upon the base and adapted to receive a band saw which extends around the lower band wheel, the beams extending to positions beside the base in position to receive the second band-wheel supporting means for the upper band wheel and pivotally secured to the base, to permit swinging of the upper band wheel to a lowered position beside the base and into a supported position upon the beams.

12. In a band saw mill, the combination of a plurality of beams arranged in approximately parallel relation, a saw mill base supported upon the beams, a band wheel car-

- ried by the base, a second band wheel supported upon the base and adapted to receive a band saw which extends around the lower band wheel, the beams extending to positions beside the base in position to receive the second band-wheel supporting means for the upper band wheel and pivotally secured to the base, to permit swinging of the upper band wheel to a lowered position beside the base and into a supported position upon the beams, and a track for a saw mill carriage extending transversely across and supported upon the beams, each of the beams extending throughout the width of the track and base.
13. In a band saw-mill, the combination of a base, a lower band wheel supported by the base in fixed position relative thereto, an upright support carried by the base, a top band wheel carried by said upright support, and pivotal means connecting the upright support with the base for swinging movement relative thereto to an approximately horizontal position.
14. In a saw mill, the combination of a base, bottom housings rigidly fixed to the base and carrying a lower band wheel, one or more top housings for supporting portions of the machine, means for rigidly holding the top housings in upright positions, and means for pivotally connecting said top housings with the base, said pivotal means being constructed and arranged to permit swinging of the top housings relative to the bottom housings to an approximately horizontal position upon detachment of the holding means.
15. In a saw mill, the combination of a base, bottom housings rigidly fixed to the base, and carrying a lower band wheel, one or more top housings for supporting portions of the machine, means for pivotally connecting said top housings with the base to permit swinging of the top housings relative to the bottom housings to an approximately horizontal position, and means for detachably securing the top housings in an upright position on the base to normally hold the same against swinging movement on the pivotal means.
16. In a band mill, the combination of a base, means for supporting a lower band wheel in a position fixed relative to the base, one or more top housings for supporting an upper band wheel for the mill, detachable means connecting the base and the housings for normally holding said housings in upright positions, and means for pivotally connecting the top housings to the base to permit swinging of the upper band wheel relative to the lower band wheel to an approximately horizontal position upon detachment of the detachable connecting means.

In testimony whereof I affix my signature.
GEORGE E. CAMPBELL.
